CLAIM

The ornamental design for ROLLED PAPER DISPENSER, as shown and described.

DESCRIPTION

FIG. 1 is a front perspective view of a ROLLED PAPER DISPENSER design;

FIG. 2 is a front view thereof;

FIG. 3 is a right side view which is a mirror image of the left side view thereof;

FIG. 4 is a rear view thereof;

FIG. 5 is a top view thereof; and

FIG. 6 is a bottom view thereof.

The broken lines in the drawings are for illustrative purpose only and form no part of the claimed design.

The Rolled Paper Dispenser is shown with symbolic breaks in its width. The appearance of any portion of the article between the break lines forms no part of the claimed design.
